UNITED STATES PATENT OFFICE.

CHARLES A. WIDMER, OF PATERSON, NEW JERSEY.

DESIGN FOR AN INDICATOR, SIGN, OR SIMILAR ARTICLE.

53,546.

Specification for Design.

Patented July 8, 1919.

Application filed August 3, 1917. Serial No. 184,351. Term of patent 14 years.

To all whom it may concern:

Be it known that I, CHARLES A. WIDMER, a citizen of the United States, residing at Paterson, in the county of Passaic and State of New Jersey, have invented a new, original, and ornamental Design for an Indicator, Sign, or Similar Article, of which the following is a specification, reference being had to the accompanying drawing, forming part thereof.

The figure is a perspective view of an indicator, sign, or similar article, illustrating my new design.

As shown in the drawings, my design consists of an indicator, sign or similar article in the form of two adjacent bands, or strips, bent substantially to the form of

a semi-circle, bearing the desired legends, each band carrying at one end an arrow, and the arrow of one band extending in a direction opposite to that of the other, the upper band being, also, widened along its upper edge, and the lower band along its lower edge, for a short distance either side of the middle of said bands, and said widened portions bearing the desired legends, and a clamp member of circular form having a lower and flaring extension connected with the bands or strips.

I claim:

The ornamental design for an indicator, sign, or similar article, substantially as shown and described.

CHARLES A. WIDMER.
